UNITED STATES PATENT OFFICE.

CARROL A. CORBETT, OF GRAND RAPIDS, MICHIGAN, ASSIGNEE, BY DIRECT AND MESNE ASSIGNMENTS, TO CORBETT-VANDEN BOS CARBURETOR COMPANY, OF GRAND RAPIDS, MICHIGAN.

CARBURETER.

1,163,393.

Specification of Letters Patent.

Patented Dec. 7, 1915.

Application filed January 9, 1915. Serial No. 1,374.

To all whom it may concern:

Be it known that I, CARROL A. CORBETT, a citizen of the United States, residing at Grand Rapids, in the county of Kent and State of Michigan, have invented certain new and useful Improvements in Carbureters; and I do declare the following to be a full, clear, and exact description of the invention, such as will enable others skilled in the art to which it appertains to make and use the same.

My invention relates to improvements in carbureters and has for its main object to provide a device of this character which may be simply and inexpensively constructed, and which may well be used for consuming low grades of fuel, provision being made whereby highly volatile fuel is provided for the initial starting of the engine equipped with the device.

To the above end, I employ a number of novel features of construction and combination hereinafter described and claimed and shown in the drawings wherein:

Figure 1 is a side elevation of a carbureter constructed in accordance with my invention; Fig. 2 is a central vertical longitudinal section thereof; Fig. 3 is a vertical transverse section as seen along the plane of the line 3—3 of Fig. 2; Fig. 4 is a horizontal section taken along the plane of the line 4—4 of Fig. 2; Fig. 5 is a detail horizontal section as seen on the line 5—5 of Fig. 1; Fig. 6 is an enlarged vertical section through the lower end of the Venturi tube and through the fuel spray nozzle; Fig. 7 is a side elevation of a tubular stem with which the nozzle is equipped; Fig. 8 is a plan view of said stem; Fig. 9 is a vertical section through a fuel cup with which the nozzle is provided; Fig. 10 is a side elevation of a valve to be described, and a vertical section of its seat and the parts adjacent thereto, and Fig. 11 is a horizontal section taken on the line 11—11 of Fig. 2.

In these drawings, constituting a part of this application, the numeral 1 designates an upright tubular body whose upper end is provided with an outstanding annular flange 2 whereby it may be connected to the intake of an internal combustion engine, while its lower end is normally closed by a removable bottom plate 3. The intermediate portion of the tube 1 is contracted internally as seen at 4 to provide means for the attachment of

an upright Venturi tube 5, above which the usual form of throttle valve 6 is located, this valve 6 being provided in the present case with an operating lever 7 located on the exterior of the body 1 and equipped with a pair of adjustable stops 8 adapted to bear against a fixed stop 9 carried by the flange 2. By this means, the throttle valve will be limited in its movement when it is being opened or closed.

As is common with devices of this character, the lower end portion of the upright tubular body 1 constitutes the fixed air intake of the carbureter, for which purpose it is here shown as provided with an opening 10 in one of its sides from which opening a tube 11 extends outwardly, which tube may, if desired, be connected to a source for supplying warm air. Actual experience has taught that carbureters constructed for instance, in one size, will not operate to equal advantage on high and low powered internal combustion engines. This is due largely to the fact that the air inlet opening 10 will not permit sufficient air to enter the carbureter, when the device is employed in connection with a high powered engine. It therefore becomes essential to provide supplemental means whereby more air may be admitted into the fixed air intake and to provide an adjustable valve for controlling the passage of air through such supplemental intake. For this purpose, I have shown one side of the upright body 1 as provided with a hollow boss 12 near its lower end, a spider 13 being formed across the opening in said boss as most clearly seen in Fig. 5. This spider is provided for the support of a stub shaft 14 (here shown in the form of a screw) upon which a valve plate 15 or disk 15 is revolvably mounted, this plate or disk being provided with a number of air inlet openings 16, equal in number to the number of openings formed in the spider 13. By this feature of construction, the valve plate 15 may be adjusted to the proper extent for allowing the necessary amount of air to enter the fixed air intake of the carbureter, after which the screw 14 may be tightened, thus permanently locking the valve plate in its adjusted position.

For the purpose of supplying fuel to the Venturi tube 5, an upright tube 20 is passed upwardly through a central opening in the bottom plate 3 and has its upper end dis-

posed in the lower end of said tube, this tube 20 being provided with a tubular extension 21 which extends laterally from one of its sides and whose outer end is shaped in the form of a cone 22 and is seated within a cone seat 23 with which one side of the body 1 is provided, this seat being located at a point directly beneath the contracted portion 4. To retain the extension 21 in this position, the side of the tube 20 opposite said extension is provided with a seat 24 in which the inner conical end of a set screw 25 is disposed, said screw being passed through an opening in one side of the body 1 as clearly disclosed in Fig. 2. It may be well to here also explain that the lower end of the tube 20 is likewise threaded through a nut 20' under the bottom plate 3. By this construction, it will be seen that by merely removing this bottom plate 3 and the set screw 25, the tube 20 and its extension 21 may be easily removed for the purpose of cleaning or repairing.

The upper end of the tube 20 constitutes a support for the fuel spray nozzle, this nozzle being most clearly shown in Fig. 6 and comprising an upright tubular stem 26 which is threaded into and rises from the upper end of the tube 20, this stem being likewise passed through the bottom 27 of a fuel cup 28 and being provided with a head 29 which contacts with the bottom of said cup to retain it in contact with the upper end of the tube 20. The head 29 is provided with a plurality of radial openings 30 which are adapted to supply fuel from the tube 20 into the cup 28, from which cup it is drawn upwardly by the air drawn through the Venturi tube. In order, however, to more readily vaporize the fuel and to cause it to more easily mix with the incoming air, the head 29 is provided with an annular laterally extending flange 31, this flange overlying the upright annular wall of the cup 28 and being spaced a slight distance above the same. By so constructing the device, fuel will be discharged from the nozzle in a circular sheet, which sheet will be intercepted by the air passing upwardly through the Venturi tube. In addition to the features just described, the head 29 is preferably provided with a rectangular projection 32 on its upper end, whereby the entire stem 26 may be readily removed.

It may be well to here explain that the spray nozzle just described is adapted only to discharge a rather low grade of fuel into the tubular body 1, this fuel usually being in the form of kerosene oil. It may also be well to explain that such oil is fed through suitable connections *c* to a float chamber C from which chamber a duct D leads to the seat 23. Disposed within the chamber C is an appropriate form of float F which is adapted, when raised by fuel within the chamber, to

actuate the needle valve V to close the inlet into said chamber. In the present device, the float is so positioned as to maintain the fuel within the chamber C at such a level as to cause it to at all times fill the cup 28, whereby an initial charge of fuel is maintained in the nozzle at all times.

In most cases, it becomes highly expedient to provide some form of valve whereby fuel may be positively prevented from flowing from the chamber C into the nozzle. In the present instance, a needle valve 40 is shown as threaded within the lower end portion of the tube 20, the active end of this valve being adapted to close the inner end of the tubular extension 21 when said valve is rotated by any suitable means with which it may be equipped.

The body 1, directly above the contracted intermediate portion 4 thereof, is shown as provided with a laterally extending branch or housing 45, this housing being provided in its lower side, with an opening 46 from which a sleeve 47 depends, said sleeve being here shown as secured to the branch by a pair of screws 48. The upper end of the sleeve 48 is of slightly less diameter than the lower end thereof and is internally threaded as most clearly disclosed at 49 in Figs. 2 and 3, these threads interengaging threads formed on the periphery of a circular spider 50 whose center is provided with an upright guide. Mounted for vertical sliding movement within this guide, is an upright needle valve 51 whose upper end is provided with a vertically adjustable cap 52 or the equivalent thereof, while its intermediate portion is equipped with an inverted cone-shaped valve 53 whose upper peripheral edge is notched as seen at 54. This valve 53 normally rests upon an annular valve seat 55 which is formed in the hollow upper end of an upright cylindrical member 56, this upper end being secured in any suitable manner within the enlarged lower end of the sleeve 47 as clearly shown.

As clearly disclosed in Figs. 2 and 3, the member 56 is provided with a chamber 57 directly beneath the valve 53, this chamber acting as the additional carbureting chamber 115 and being provided with a number of air inlets 58 and with a fuel inlet 59, the latter discharging centrally through the bottom of the recess or chamber 57 and being normally closed by the pointed lower end of the needle valve 51 while the former (the openings 58) are controlled by a perforated valve sleeve 60 which is revolvably mounted upon the member 56 and which contacts with the shoulder thereon. This sleeve 60 is preferably provided with a laterally extending arm 61 to which an appropriate link may be connected for adjusting said sleeve from a remote point.

By the construction just described, it will

be seen that discharge of mixture from the additional carbureting chambers is controlled by the valve 53, which valve however, may be raised against the tension of its spring 53', when suction is created above said valve. Such suction however, cannot be created until the valve 41 has been closed and until other adjustments to be described have first been made.

10 Disposed in the top of the branch or housing 45, at a point directly above the opening 46 therein, is a supplemental air intake 70 which is here shown as controlled by an inwardly opening cone valve 71, this valve being normally closed by a coil spring 72 and being provided with a rod 73 which is threaded through the center of its stem and projects into the housing therefrom. Interposed between the lower end of the rod 73 and the upper end of the cap 52, is a transverse horizontal shaft 75 upon which a double-acting cam 76 is secured, this cam being disposed within the housing 45 and being adapted to lock either the valve 53 or 25 the valve 71 against opening. As shown in the drawings (see Fig. 2), the cam is locking the valve 71 in closed position, the valve 41 is closed, thus preventing the passage of kerosene into the carburetor, and the valve 30 53 is free to open the moment suction is created above the same, this being the normal condition of parts when starting the engine with which the device is provided. By such positioning of parts, it will be seen 35 that gasoline or other highly explosive fuel will be drawn into the engine cylinders until the latter become heated by the operation of said engine. After this has been accomplished, it becomes expedient to lock the 40 valve 53 against opening, to allow the supplemental air intake valve 71 to open, and to dispose the valve 41 in such a manner as to allow kerosene to be drawn into the engine cylinders. For accomplishing this result, one end of the shaft 75 is provided 45 with a crank arm 80 connected by a link 81 to a crank arm 82 which is secured to an additional horizontal shaft 83 which extends transversely through the body 1 and 50 the Venturi tube, said shaft 83 carrying the valve 41 as most clearly disclosed in Figs. 1 and 2. The arm 82 is here shown as provided with a rod 84 by means of which it may be shifted, it being therefore seen that 55 actuation of this single rod 84, in the proper direction, will open the valve 41, and will rotate the cam 76 from the position seen in full lines in Fig. 2 to that seen in dotted lines therein, thus preventing the valve 53 60 from opening, and thereby excluding all gasoline from the carburetor. It will likewise be evident that the supplemental air intake valve 71 is then free to act. On the other hand, however, when the valve 41 is 65 closed to prevent the discharge of kerosene

into the carburetor, the supplemental air intake valve 71 is locked against opening, and the additional or gasoline mixing chamber is allowed to discharge into the carburetor. It may here be further explained, that when 70 initially starting the engine, the arm 61 is actuated to rotate the valve sleeve 60 to close the openings 58, thus causing the engine cylinders to draw in pure gasoline. By this means, they are effectively primed and 75 it is insured that quick starting will result. The arm 61 may then be operated in the proper direction to expose the openings 58 to the necessary extent, thus feeding the proper mixture to the engine, the latter being now allowed to run upon the gasoline 80 for a suitable length of time, after which the rod 84 is shifted to open the valve 41 and prevent opening of the valve 53. As hereinbefore explained, this operation causes 85 the carburetor to supply a mixture of kerosene and air to the engine, but if the latter does not readily run upon such mixture, it is simply necessary to again operate the rod 84 to momentarily check the supply of kerosene and admit gasoline. This may be successively done until the engine will effectively run upon the kerosene mixture alone. 90

From the foregoing description, taken in connection with the accompanying drawings, it will be seen that a comparatively simple carburetor has been provided for carrying out the objects of the invention, that such carburetor will effectively operate upon fuels of either high or low grade, and 95 that a number of very novel features have been provided for constructing the device in such a manner as to allow such operation to take place. Among these novel features, is the construction and arrangement of parts 100 whereby the two valves 51 and 53 are operated simultaneously, the former controlling the admission of fuel into the mixing chamber 57, while the latter controls the discharge of mixture therefrom. It is evident 105 that this construction effectively accomplishes the results for which it is designed yet that it is extremely simple. Furthermore, it is highly desirous to provide the upper peripheral edge of the valve 53 110 with the notches 54, since a pin may be dropped through the spider 50 and into these notches to prevent rotation of the valve, when the cap 52 is being rotated and 115 adjusted on the needle valve 51, it being understood that the sleeve 47 and the parts carried thereby, are first removed from the housing 45, before such adjustments can be made, and that the pin above mentioned 120 prevents rotation of both of the valves, thus 125 allowing the cap to be readily rotated thereon for accomplishing the necessary adjustment.

I claim:

1. In combination, a pair of carbureting

chambers having mixture outlets, a pair of manually operable shafts rotatable in unison, a valve for one outlet actuated by one of said shafts, a suction opened valve for the other outlet, and a locking device actuated by rotation of the other shaft and preventing opening of said suction opened valve when the other valve is opened.

2. In combination, a pair of carbureting chambers having mixture outlets, a pair of manually operable shafts rotatable in unison, a valve for one outlet actuated by one of said shafts, a suction opened valve for the other outlet, and a locking cam actuated by the other shaft and preventing opening of said suction opened valve when the other valve is opened.

3. In combination, a pair of carbureting chambers having mixture outlets, a pair of manually operable shafts rotatable in unison, a rotatable valve actuated by one shaft and controlling the outlet of one carbureting chamber, a suction opened valve controlling the discharge of mixture from the outlet of the other carbureting chamber, and a locking cam carried by the other shaft and engaging a part of the suction opened valve when the rotatable valve is opened, whereby to lock said suction opened valve against opening.

4. A carbureter comprising a carbureting chamber having fuel and air inlets, a supplemental air inlet, and a valve for the latter, an additional carbureting chamber having a highly volatile fuel inlet, an air inlet, a mixture outlet, and a valve for controlling the latter, combined with a double acting locking member for locking either of the two valves against opening.

5. A carbureter comprising a carbureting chamber having fuel and air inlets, a supplemental air inlet, and a valve for the latter, an additional carbureting chamber having a highly volatile fuel inlet, an air inlet, a mixture outlet, and a valve for controlling the latter, combined with a double acting locking device for locking either of the two valves against opening, an additional valve controlling the discharge of mixture from the first mentioned carbureting chamber, and means to simultaneously operate the locking device and the additional valve.

6. A carbureter comprising a carbureting chamber having fuel and air inlets, a supplemental air inlet, and a valve for the latter, an additional carbureting chamber having a highly volatile fuel inlet, an air inlet, a mixture outlet, and a valve for controlling the latter, combined with a double acting cam for locking either of the two valves against opening, a shaft upon which said cam is mounted, an additional valve for controlling the discharge of mixture from the first named carbureting chamber, an additional shaft upon which said additional

valve is mounted, and means connecting the two shafts to simultaneously operate the same.

7. A carbureter comprising a carbureting chamber having an air inlet, a fuel inlet, and a branch above said inlets, an additional carbureting chamber communicating with the interior of said branch and having a highly volatile fuel inlet, and an air inlet, a supplemental air inlet likewise communicating with the interior of said branch, a valve for controlling said supplemental air inlet; an additional valve for controlling the discharge of mixture from the additional carbureting chamber, and a double acting locking member disposed within the branch and adapted to be actuated to lock either of the two valves against opening.

8. A carbureter comprising a carbureting chamber having a Venturi tube disposed between its ends, an air intake and a fuel intake contiguous to one end of said Venturi tube, a branch projecting laterally from the carbureting chamber adjacent the other end of said tube, an additional carbureting chamber communicating with said branch and having a highly volatile fuel inlet and an air inlet, a valve for controlling the discharge of mixture from the additional carbureting chamber into the branch, a supplemental air inlet into said branch, a valve controlling said supplemental air inlet, a double acting locking member adapted to lock either of the valves against opening, and an additional valve in said Venturi tube.

9. A carbureter comprising a carbureting chamber having a Venturi tube disposed between its ends, an air intake and a fuel intake contiguous to one end of said Venturi tube, a branch projecting laterally from the carbureting chamber adjacent the other end of said tube, an additional carbureting chamber communicating with said branch and having a highly volatile fuel inlet and an air inlet, a valve for controlling the discharge of mixture from the additional carbureting chamber into the branch, a supplemental air inlet into said branch, a valve controlling said supplemental air inlet, a double acting locking member adapted to lock either of the valves against opening, an additional valve in said Venturi tube, and connections between said locking device and said additional valve, for operating the two simultaneously.

10. The combination with a fuel passage-way, of means for supplying a fuel mixture of relatively low combustibility, a cut-off device for the latter, means for supplying to said passage-way a fuel mixture of relatively high combustibility, said means including a suction opened combination valve for controlling the entrance of both air and the highly combustible fuel, a supplemental

air intake for permitting pure air to enter said passage-way, and means for locking said combination valve in closed position.

11. In combination with a fuel passage-way, of means for feeding a fuel mixture of relatively low combustibility thereto, a cut-off device for said means, a supplemental air intake for admitting pure air to said passage-way, means for admitting to said 10 passage-way a fuel mixture of relatively high combustibility, said means including a combination valve for cutting off both air

and a high explosive fuel, means independent of said combination valve for controlling the amount of air supplied to it, and 15 means for locking said combination valve.

In testimony whereof I have hereunto set my hand in presence of two subscribing witnesses.

CARROL A. CORBETT.
